INPUT COMPONENT FOR A DATA PROCESSING SYSTEM

Norman J. Rosen, Altadena, and Melvin H. Best, Pasadena, and Clair A. Samhammer, Altadena, Calif., assignors to Datex Corporation, Monrovia, Calif., a corporation of California

Filed Oct. 26, 1961, Ser. No. 67,264

Term of patent 14 years

(Cl. D26—5)

FIGURE 1 is a front perspective view of an input component for a data processing system showing our new design; and

FIGURE 2 is a rear elevational view, on a reduced scale, of the input station of FIG. 1.

The side of the input component opposite to the side shown in FIG. 1 is plain, unornamented and similar to the illustrated side.

It is understood that the recessed panel contains vertical rows of apertures in the alignment indicated by the broken lines therein.

We claim:

The ornamental design for an input component for a data processing system, as shown and described.
